UNITED STATES PATENT OFFICE.

SAMUEL MILLER, OF PHILADELPHIA, PENNSYLVANIA.

GAME.

Application filed November 1, 1927. Serial No. 230,240.

My invention relates to games and more particularly to that type of game in which the player is blind-folded and required to attach an article to a chart or representation 5 of some object.

In games of this nature, the player must depend solely upon his or her sense of direction in affixing the article to the chart and one of the objects of this invention is to 10 provide a game in which the efforts of each player are rewarded or penalized in such a manner as to add to the amusement of the other players.

Another object of the invention is to so 15 divide the chart, to which the article is to be attached, that it will be impossible for a player to remember locations of certain legends regardless of how well his or her sense of direction is developed.

20 These objects and other advantageous ends which will appear hereinafter, I attain in the following manner, reference being had to the accompanying drawing in which,

Figure 1 represents a chart embodying 25 my invention, and

Figure 2 a plan view of an article adapted to be pinned or otherwise secured, by a blind-folded player, to the chart shown in Figure 1.

The chart 5 may be made of any suitable 30 material upon which a figure can be produced and which may be readily supported upon a wall or other convenient place. Chart 5 has been shown as being rectangular in outline and preferably has a figure formed on its 35 face which is divided into a plurality of small spaces.

This figure may be of any design and may consist of several figures imposed upon one another. The figure shown in the drawing 40 consists of a circle 6 traversed by ten lines 7 which extend between five points spaced around its periphery so that a five-pointed star 8 is formed. A line 9 extends from each point of star 8 to the periphery of the center 45 space which has been shown as being a small circle 10. A line 11 extends from the periphery of circle 10 intermediate adjacent lines 9 and joins the periphery of circle 6 intermediate the points of star 8. In this 50 manner, circle 6 and star 8 are divided into a plurality of spaces 12 of irregular shape and size.

The periphery of star 8 has been shown

in heavy lines, while lines 9 and those portions of lines 7 and 11 falling within star 55 8 are lighter, but the several spaces 12 are preferably of different colors and the colored spaces so assorted that each space of one color is flanked on all sides by spaces of other colors, thus giving the chart an unusual appearance.

The game may be called any appropriate name, but for the sake of illustration, it has been designated as "Crown" and this word is inscribed within circle 10. The article, 65 which the blind-folded player is required to affix to chart 5, has been shown as being a small disc 13 of any suitable material upon which the name of the game is also preferably inscribed. Spaces 12 contain legends, 70 the majority being preferably in rhyme, each of which instruct the player, or players, what to do in case the blind-folded player affixes disc 13 on that space.

Chart 5 having been secured to a wall or 75 other suitable support, a player is stationed ten or fifteen feet from the chart, blind-folded and turned around a few times, so that his sense of direction is lost or disturbed, and instructed to affix disc 13 to chart 5. If 80 the player succeeds in affixing disc 13 over circle 10, he is entitled to some reward or prize previously decided upon. If disc 13 is affixed over one of the spaces 12, the player must follow the instructions contained in that 85 space, which may be either in the nature of a penalty or a reward, or the legend in that particular space may require the entire group of players to do something; the instructions preferably being such that the carrying out 90 of them will add to the hilarity of the assembled players.

While I have illustrated and described a certain embodiment of my invention and have described a method of using same, it is evident 95 that the game may be adapted to many variations, and hence I do not wish to limit myself to the precise construction and method described herein, but consider that I am at liberty to make such changes and applications as fairly come within the scope of the appended claim.

I claim:—

A game comprising a playing piece and a chart upon which the playing piece is to be 105 placed by a blindfolded player, the chart

having a small circle at its center upon which the player endeavors to place the playing piece, a large circle concentric with the small circle, a star inscribed in the large circle, 5 lines extending from the small circle to the periphery of the large circle at and intermediate the points of the star for dividing

the star and large circle into spaces, and a legend in each space designating an act which must be performed by the player who places 10 the playing piece upon that space.

In testimony whereof I have signed my name to this specification.

SAMUEL MILLER.
